UNITED STATES PATENT OFFICE.

ISIDOR TANNENBAUM, OF NEW YORK, N. Y.

DESIGN FOR A WATCHCASE.

Application filed June 26, 1925. Serial No. 13,912. Term of patent 3 $\frac{1}{2}$ years.

To all whom it may concern:

Be it known that I, ISIDOR TANNENBAUM, a citizen of the United States, doing business as I. TANNENBAUM Co., at 121 Canal Street, in the county of New York and State of New York, have invented a new, original, and ornamental Design for Watchcases, of which the following is a specification, reference being had to the accompanying drawing, forming part thereof.

Figure one (1), is a plan view of the

watch case, showing the ornamental design of the face of the case, and the rectangular shaped crystal.

Figure two (2). is a side view of the case, showing the ornamental design around the center.

I claim:

The ornamental design for a watchcase as shown.

ISIDOR TANNENBAUM.
